ARTICLE OF FOOTWEAR AND CORRECTIVE SOLE THEREFOR

Hyman L. Whitman, East Bridgewater, Mass., assignor to The B. F. Goodrich Company, New York, N. Y., a corporation of New York

Application October 18, 1946, Serial No. 703,951

12 Claims. (Cl. 36—71)

1

This invention relates to an article of footwear and to an outer supporting element adapted for use therein, and particularly to a supporting element for the outer edge of the foot for use with shoes provided with a unified sole arch support.

The present application is concerned particularly with an outer supporting element to be used in conjunction with an arch support such as is disclosed in U. S. Patent No. 1,938,127, granted to me December 5, 1933, or with a unified sole arch support as set forth in U. S. Patent No. 2,054,151, granted to me September 15, 1936.

The principal objects of this invention are to equalize the rotational effect on the foot imparted by an arch support, to control the calcaneal twist imparted to the heel by the inclined heel element, to provide a cushion for the sensitive area at the base of the fifth metatarsal of the wearer's foot, and to distribute the body weight so as to give the correct three point pressure distribution on the plantar surface of the foot.

The use of an inclined arch support and inclined heel element in cases of pronation of the arch has been discussed at length in the patent previously referred to. The principle involves correctly supporting the tripod construction of a foot consisting of the os calcis, the scaphoid and the astragulus. The corrective effect is attained by means of a relatively non-resilient heel element inclined downwardly from the inner border of the sole directly under the os calcis. A resilient arch support member coincidentally abuts the forward edge of the heel element along a reversely curved line extending inwardly from the inner border of the sole, forming a recess at the area of sensitivity of the plantafascia tendon, which extends longitudinally through the arch. The arch support member is preferably higher than the heel element at the abutting edge, with the greatest height differential being at the inner border of the sole to provide for wearing adjustment at first.

Such a sole arch support is designed to correct pronation caused by an inward rotation and flattening of the os calcis, scaphoid and astragulus. The effect of the sole arch support is to realign the tripod construction by supporting and outwardly rotating the bones involved without exerting undue pressure on the sensitive area of the plantafascia tendon. The use of such inner border support, however, gives a rolling sensation to the wearer and distributes too much of the body weight along the entire lateral outer

2

border of the foot due to the calcaneal twist imparted to the heel. This effect is especially noticeable at the base of the fifth metatarsal, which is in many cases an extremely sensitive area. The present invention involves the use of an outer supporting element to minimize the rolling sensation caused by the arch support, to control the degree of calcaneal twist, and to provide support for the foot along the outer lateral border in such a way as to distribute the body weight at three clearly defined points on the plantar surface of the foot, whereby the base of the fifth metatarsal is relieved of an undue burden and is cushioned to relieve the sensitiveness in that region.

The invention is best understood by reference to a preferred embodiment, as shown by the accompanying drawing of which:

Fig. 1 is a plan view of the inner face of a sole having thereon an arch support member, a heel element, and an outer supporting element; part of the sole being broken away for clarity of illustration;

Fig. 2 is a side elevation of a sole prepared in accordance with this invention and illustrating the respective elevations of the corrective elements;

Fig. 3 is a section taken on line 3—3 of Fig. 2;

Fig. 4 is a section taken on line 4—4 of Fig. 2;

Fig. 5 is a perspective view illustrating the preferred shape of the outer supporting element; and

Fig. 6 is a perspective view illustrating the relation of the outer supporting element to the bony structure of a foot located on the sole.

In the preferred embodiment of the invention as illustrated by the accompanying drawing, a sole 10 is built up of alternate layers of rubber 11 and square woven fabric 12, although any of the conventional sole constructions may be used. Suitably oriented on the normal upper face 13 of the sole 10 are an arch support member 14, a heel element 15, and an outer supporting element 16. The arch support member 14 and the heel element 15 are disposed in the marginal region adjacent to the inner border 17 of the sole 10 and are raised above the normal upper face 13 of the sole along this border from which border they slope downwardly toward the outer border 18 of the sole 10 to converge with the normal thickness of the sole 10 along a feather edge 19.

The arch support member 14 is preferably of a resilient material such as a sponge rubber, so as to exert a rotating action on the foot while having a degree of resiliency to cushion the base

of the first metatarsal and the plantafascia tendon. The rear edge 20 of the member 14 is preferably recessed inwardly from the inner border 17 of the sole 10 toward the outer border 18 thereof in a reversely curved edge which coincidentally abuts the forward edge 21 of the heel element 15. This reversely curved edge allows the heel element 15 to extend forward along the inner border 17 of the sole to the point at which the plantafascia tendon dips sharply downwardly toward the plantar surface of the foot.

The heel element 15 is preferably of a relatively non-resilient material, such as hard rubber, so as to provide a firm support to elevate and rotate the os calcis 22, astragulus 23 and scaphoid 24 toward the outer border 18 of the sole 10 preventing pronation to the inner border 17. The heel is skived downwardly and away from the inner border 17 in the same manner as the arch support member 14, and converges with the normal upper face 13 of the sole along a common longitudinal feather edge 19 with the arch support member 14.

The use of an inner border support such as has just been described rotates the foot toward the outer border thereof and gives the wearer a rolling sensation. The heel element, in particular, imparts what is commonly referred to as calcaneal twist to the heel. Such a construction relieves the undue pressure which is exerted on the inner border of the foot due to pronation of the arch, but in so doing gives somewhat faulty weight distribution on the outer border of the foot. This is especially noticeable in the sensitive area of the base of the fifth metatarsal 25. I have discovered that the objections enumerated are overcome by the use of an outer supporting member 16 disposed in the marginal region adjacent to the outer border 18 of the sole.

The outer supporting element is preferably of a resilient material such as sponge rubber so as to cushion the base of the fifth metatarsal 25 as well as to provide lateral support for the foot. In the preferred embodiment as shown in Fig. 5, the outer supporting element presents an essentially planar upper face 26 adapted to lie essentially parallel to the normal upper face 13 of the sole 10. This planar surface 26 extends inwardly from the essentially linear outer edge 27 of the element along which edge the element 16 is of maximum vertical thickness. The upper face of the element slopes sharply downwardly from the inner border 28 of the planar surface 26 to an arcuate feather edge 29 which forms the inner edge of the element, whereby the supporting element converges with the normal thickness of the sole 10.

The outer supporting element 16 is disposed laterally to the arch support element 14 on the sole 10 with the longitudinal axis of the outer element being generally parallel to the longitudinal axis of the sole. The planar upper face 26 extends inwardly for a sufficient distance to extend under the base of the fifth metatarsal of a foot located on the sole. At the widest part of the supporting element the arcuate edge 29 thereof abuts the feather edge 19 of the arch support member 14. Thus the arch of the foot is cradled between the sole arch support and the outer lateral support.

This outer supporting element controls the degree of calcaneal twist imparted by the inclined inner border portion and thus prevents excessive rotation of the foot toward the outer border. The raised planar surface of the element shifts the

body weight forward along the outer border and the complete sole assembly gives a clearly defined three-point weight distribution on the plantar surface of the foot, as indicated by the dotted line 30 of Fig. 1 with the pressure points being at points 31, 32 and 33, respectively. This relieves the sensitivity in the region at the base of the fifth metatarsal and the resilient material comprising the supporting element further acts as a cushion for that area.

The outer supporting element does not and is not intended to support the cuboid bone 34, as can readily be seen from Fig. 6. The effect of the element on the cuboid is negligible since the support is not localized at that point, the only upward thrust on the cuboid being that transmitted from the fifth metatarsal through the articulation of the metatarsal with the cuboid.

The outer supporting element may be used in any case where it is desired to control the calcaneal twist of the heel, and the outward rotation of the foot, while the sole arch support described in detail is preferably used in combination with the outer supporting element. The element may be used in conjunction with any inner border support. The element is preferably of a resilient material so as to cushion the sensitive base of the fifth metatarsal. Sponge rubber is preferably used, but any suitable relatively resilient material such as soft cork, soft vulcanized rubber, or similar materials may be used if desired. The invention may be embodied in any type of foot-wear where an arch support is used.

In the preferred embodiment for use in tennis shoes and the like, the arch support member, heel element, and outer supporting element are sandwiched in below the top layer of fabric on the sole. If desired, a protective shield of a material impervious to perspiration may be used as an upper face for the sole as a whole or for the corrective element. The sole itself may comprise a resilient soft rubber, in which case the arch support member and outer supporting element may comprise molded raised portions on the sole proper. Similarly, if the sole is of a substantially non-resilient material, the heel element may comprise an integral molded portion of the sole proper.

The invention has been described in considerable detail with reference to certain preferred embodiments, but it will be understood that the outer supporting element may be constructed of any suitable resilient material; the shape thereof may be changed or modified if done so in view of the principles already set forth and the objectives to be attained by use of the element; the outer supporting element may be incorporated in an insole, or may be used as a separate element, and other similar variations and modifications may be effected without departing from the spirit and scope of the invention as defined in the appended claims.

I claim:

1. A supporting element in combination with a sole and arch support member, said element being laterally disposed in the outer marginal region of said sole generally opposite said support member and comprising a raised portion in said region presenting a raised generally planar surface substantially parallel to the sole face supporting the base of the fifth metatarsal and sloping downwardly to the face of said sole portion along the inner edge of said element.
2. A resilient element in combination with a sole and arch support member, said element be-

ing disposed in the region of the sole below the base of the fifth metatarsal and comprising a raised portion along the outer longitudinal marginal region of said sole opposite said arch support member presenting a raised generally planar surface substantially parallel to the sole face and supporting the base of the fifth metatarsal and sloping downwardly from said raised portion to converge with the face of said sole portion along the inner edge of said element.

3. A combination corrective sole and outer supporting element, said sole having a raised member on the upper face along the inner border thereof sloping downwardly therefrom towards the outer border thereof to converge with the normal thickness of said sole, said outer supporting element being disposed in the outer marginal region of said sole laterally to said raised portion and comprising a resilient element projecting above the normal face of the sole presenting a raised generally planar surface substantially parallel to the sole face supporting the base of the fifth metatarsal and sloping downwardly along the inner edge of said element to converge with the normal upper face of said sole.

4. A combination corrective sole and outer supporting element, said corrective sole comprising a raised heel element on the upper face thereof having the highest portion of the said heel element at the inner border of said sole and sloping downwardly towards the outer border of said sole, the forward edge of said heel element being reversely curved inwardly from the inner border of said sole towards the outer border thereof, said corrective sole further comprising an arch support member having the rear edge thereof coincidentally abutting the reversely curved edge of said heel element and being of different height and resiliency than said heel element, said arch support member comprising a raised portion along the inner border of said sole tapering downwardly towards the outer border thereof to converge with the normal thickness of said sole, said supporting element being disposed in the outer marginal region of said sole laterally to said arch support member and comprising a resilient raised portion presenting a raised generally planar surface substantially parallel to the sole face supporting the base of the fifth metatarsal and sloping downwardly along the inner edge therof to converge with said sole.

5. A sole having associated therewith an arch support member, a corrective heel element and an outer supporting element, said arch support member and heel element comprising abutting raised portions in the inner marginal region of said sole and sloping downwardly from the inner border of said sole towards the outer border thereof to converge with the normal thickness of said sole, said outer supporting element comprising a resilient element disposed in the region below the fifth metatarsal of a foot located thereon, said resilient element extending generally longitudinally in said region and comprising a raised surface along the outer border of said sole presenting a raised generally planar surface substantially parallel to the sole face and supporting the base of the fifth metatarsal and being skived along the inner edge of said element to converge with the normal thickness of said sole.

6. An outer supporting element in combination with a corrective sole comprising an arch support member and a corrective heel element, said arch support member and heel element being disposed in coincidentally abutting relation on

the inner marginal region of the upper face of said sole with the abutting rear edge of the arch support member being recessed in a reversely curved manner inwardly from the inner border of said sole, said arch support member and heel element presenting surfaces raised above the normal face of said sole with the highest point on each respective surface being adjacent to the inner border of said sole from which said surfaces slope downwardly toward the outer border of said sole to converge at a feather edge with the normal thickness of said sole, said supporting element comprising a resilient element disposed longitudinally in the marginal region of said sole adjacent to the outer border thereof, said supporting element presenting a raised essentially planar surface extending substantially parallel to the normal thickness of said sole from the outer border thereof to the region beneath the fifth metatarsal of a foot located thereon and thereafter sloping downwardly to a feather edge along the inner edge of said element whereby said edge converges with the normal thickness of said sole.

7. An outer supporting element for shoes comprising a resilient material presenting an essentially planar upper face extending inwardly from the essentially linear outer edge thereof along which edge said element is of maximum vertical thickness, said upper face being generally parallel to the plane of the lower face of said element, said element tapering downwardly from the inner border of said essentially planar surface to the substantially arcuate feather edge which comprises the inner edge of said element.

8. A corrective sole comprising an arch support member, a heel element and an outer supporting element, said arch support member comprising a resilient raised portion skived inwardly from the outer border of said sole at which border said member is of maximum vertical thickness, said arch support member having the rear edge thereof recessed from the inner border of said sole towards the outer border thereof in a reversely curved edge which coincidentally abuts the forward edge of the said heel element, said heel element comprising a relatively non-resilient raised portion skived downwardly from the inner border of said sole where said element is of maximum vertical thickness towards the outer border thereof where said element converges with the normal upper face of said sole along a feather edge, said outer supporting element comprising a resilient element disposed longitudinally in the outer marginal region of said sole and presenting an essentially planar upper face extending inwardly from the essentially linear outer edge thereof along which edge said element is of maximum vertical thickness to the region beneath the fifth metatarsal of a foot located thereon, said element tapering downwardly from the inner border of said essentially planar surface to the substantially arcuate inner edge of said element wherein said supporting element converges with the normal upper face of said sole.

9. An article of footwear comprising a combination corrective sole and outer supporting element, said sole having a raised member on the upper face along the inner border thereof sloping downwardly therefrom toward the outer border thereof to converge with the normal thickness of said sole, said outer supporting element being disposed in the outer marginal region of said sole laterally to said raised portion and comprising a resilient element projecting above the normal face of the sole presenting a raised

generally planar surface substantially parallel to the sole face supporting the base of the fifth metatarsal and sloping downwardly along the inner edge of said element to converge with the normal upper face of said sole.

10. An article of footwear comprising a corrective sole and outer supporting element, said corrective sole comprising a raised heel element on the upper face thereof having the highest portion of the said heel element at the inner border of said sole and sloping downwardly toward the outer border of said sole, the forward edge of said heel element being reversely curved inwardly from the inner border of said sole toward the outer border thereof, said corrective sole further comprising an arch support member having the rear edge thereof coincidentally abutting the reversely curved edge of said heel element and being of different height and resiliency than said heel element, said arch support member comprising a raised portion along the inner border of said sole tapering downwardly toward the outer border thereof to converge with the normal thickness of said sole, said supporting element being disposed in the outer marginal region of said sole laterally to said arch support member and comprising a resilient raised portion presenting a raised generally planar surface substantially parallel to the sole face supporting the base of the fifth metatarsal and sloping downwardly along the inner edge thereof to converge with said sole.

11. An article of footwear comprising an upper, an outer supporting element, and a corrective sole which comprises an arch support member and a corrective heel element, said arch support member and heel element being disposed in coincidentally abutting relation on the inner marginal region of the upper face of said sole with the abutting rear edge of the arch support member being recessed in a reversely curved manner inwardly from the inner border of said sole, said arch support member and heel element presenting surfaces raised above the normal face of said sole with the highest point on each respective surface being adjacent to the inner border of said sole from which border said surfaces slope downwardly toward the outer border of said sole to converge at a feather edge with the normal thickness of said sole, said supporting element comprising a resilient element disposed longitudinally in the marginal region of said sole adjacent to the outer border thereof, said supporting element presenting a raised essentially planar surface extending

substantially parallel to the normal upper face of said sole from the outer border thereof to the region beneath the fifth metatarsal of a foot located thereon and thereafter sloping downwardly to a feather edge along the inner edge of said element whereby said edge converges with the normal thickness of said sole.

12. An article of footwear comprising a corrective sole and an upper, said corrective sole comprising an arch support member, a heel element and an outer supporting element, said arch support member comprising a resilient raised portion skived inwardly from the outer border of said sole at which border said member is of maximum vertical thickness, said arch support member having the rear edge thereof recessed from the inner border of said sole toward the outer border thereof in a reversely curved edge which coincidentally abuts the forward edge of the said heel element, said heel element comprising a relatively non-resilient raised portion skived downwardly from the inner border of said sole where said element is of maximum vertical thickness toward the outer border thereof where said element converges with the normal upper face of said sole along a feather edge, said outer supporting element comprising a resilient element disposed longitudinally in the outer marginal region of said sole, and presenting an essentially planar upper face extending inwardly from the essentially linear outer edge thereof along which edge said element is of maximum vertical thickness to the region beneath the fifth metatarsal of a foot located thereon, said element tapering downwardly from the inner border of said essentially planar surface to the substantially arcuate inner edge of said element wherein said supporting element converges with the normal upper face of said sole.
